CLAIM

The ornamental design for a set of side view mirrors for an automotive vehicle body as shown and described.

DESCRIPTION

FIG. 1 is a front and left side perspective view of a set of side view mirrors for an automotive vehicle body showing my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof; and,

FIG. 7 is a bottom plan view thereof.

The portions of the vehicle shown in broken lines are for environmental and illustrative purposes and form no part of the claimed design.
